UNITED STATES PATENT OFFICE.

LOUIS LEVIEN, OF NEW YORK, N. Y., ASSIGNOR TO CHARLOTTE MICHELBACHER, OF SEAGATE, LONG ISLAND, NEW YORK.

SERVING TRAY.

Application filed August 16, 1927. Serial No. 213,237.

This invention relates to improvements in serving trays and similar articles and more particularly to improvements in holders made of glass, ceramic material, metal, or 5 any other suitable material, for holding glasses.

A particular object of my invention is to provide a combination glass holder and ash tray made of glass or any suitable material 10 for use on tables.

Another object of my invention is to provide a combination glass holder and ash tray which will be as compact as possible and which will be adapted to be used on the corner or edge of any suitable table.

Another object of my invention is to provide a combination holder which will also hold cigarettes.

Further objects of this invention will be 20 apparent from the specification and drawings in which

Fig. 1 is a plan view showing a bridge table equipped with two of my improved trays on adjoining corners thereof.

25 Fig. 2 is an enlarged plan view showing my improved tray in position.

Fig. 3 is a plan view of the bottom of my improved tray showing how same is located on the table, the table being shown partly 30 broken away to show the relation of the parts.

Fig. 4 is a vertical sectional view along the line 4—4 of Fig. 2 showing the tray in position and holding glasses, cigarettes, etc.

35 Fig. 5 is a vertical sectional view along the line 5—5 of Fig. 2.

Fig. 6 is a sectional view on the line 6—6 of Fig. 2.

Accessories for bridge tables must necessarily occupy a minimum of space and for 40 this reason I have devised a holder for glasses and cigarettes equipped with an ash tray which is designed to be set upon the corner of a bridge table out of the way of the players and which preferably can be made or cast 45 from one piece of glass with the exception of the retaining means which are attached to the underside of the tray.

In the drawing 10 represents the body of the tray, which is preferably made of glass 50 or similar ceramic material having the circular rims 11 for holding glasses, 12. Cen-

trally located between the two glass holders 11 is the rectangular cigarette holder 13 and for convenience of illustration I have shown said holder 13 containing cigarettes 14, as 55 shown in Fig. 2. I do not wish to limit my invention to any particular relative location of the cigarette holder as it is to be understood that the embodiment shown herein is merely illustrative, and that I am not limited 60 to the details shown therein.

15 is a depression in the body of the holder for holding matches or similar articles. 16 and 17 represent depressed portions of the body of the tray which will serve as receptacles for ashes. 18 is a ridge between the ash receptacles 16 and 17. 19 and 20 are depressions formed in the glass which serve as holders for cigarettes. Said depressions 19 and 20 are not aligned, so that the adjacent ends of cigarettes, etc., placed therein will not contact. 21 and 22 are indentations or depressions in the body of the holder 10 in which the ends of the metal clamp 24 engage so as to hold the tray securely on 70 the bridge table. The clamp 24 is preferably made of spring metal and has one end thereof terminating at the apex of the triangle forming the tray (see Figure 2), the other ends of the holder engaging the depressions 75 21 and 22 indicated. That is, one arm of the clamp 24 is adapted to bear upon the underside of the table and this arm has two spring arms, which extend above the table and engage the recesses 21 and 22.

85 In order to hold the device in position, it is only necessary to have its depressions 21 and 22 engaged by spring arms which are connected to any suitable part or parts extending under the table to clamp the holder 90 in position, and I do not wish to limit myself to the specific form of clamp illustrated.

Likewise, I prefer to have the holder of 95 triangular shape, but I do not wish to be limited to this shape.

Having fully described my invention, what I claim is:

1. A table tray for glasses and the like, of triangular form having receptacles therein, recesses formed in said tray on two edges 100 thereof and a separate spring clamp associated with said tray, said clamp having

three arms, two of said arms being engaged in said recesses and the third of said arms bent to resiliently engage the underside of the table.

5 2. A tray for glasses and the like, of substantially triangular form, receptacles therein, recesses formed on two edges of said tray

and a spring clamp associated with said tray, said spring clamp having three arms, two of which fit into said recesses and the third being bent to resiliently engage the underside of the table.

In testimony whereof I affix my signature.
LOUIS LEVIEN.
